UNITED STATES PATENT OFFICE

ALEXANDER MARTINEK, OF WORCESTER, MASSACHUSETTS, ASSIGNOR TO PRAGER CO., INC., A CORPORATION OF NEW YORK

DESIGN FOR WALL PAPER OR SIMILAR ARTICLE

Application filed September 2, 1931. Serial No. 40,982. Term of patent 3½ years.

To all whom it may concern:

Be it known that ALEXANDER MARTINEK, a citizen of the United States, residing at Worcester, in the county of Worcester and State of Massachusetts, has invented a new, original, and ornamental Design for Wall Paper or Similar Article, of which the following is a specification.

In the accompanying drawing:—

The figure is a surface view of a piece of wall paper or similar article showing the design. The area within the dot and dash lines, A, B, C and D represent one complete unit of design. The design repeats at the sides. At the top and bottom edges the design extends completely to the top and bottom edges of the wall paper.

I claim:—

The ornamental design for wall paper or similar article as shown and described.

In testimony whereof I affix my signature.

ALEXANDER MARTINEK.
